STORM SHIELD FOR WINDOWS

Clinton A. Grimes, Philadelphia, Pa.

Application August 6, 1938, Serial No. 223,535

3 Claims. (Cl. 156—15)

This invention relates to improvements in attachments for windows and pertains particularly to an improved rain shield.

The present invention has for a primary object to provide an improved shield device designed for connection with a window frame upon the outer side thereof by means of which the driving of rain into the window when the latter is open, is prevented, thus eliminating the necessity of attending to the closing of open windows when a rainstorm develops, the shield being of automatic character whereby it will move from a normal open position to a closed position when rain falls thereon.

Another object of the invention is to provide a window opening shield which normally maintains a position relative to the opening which will permit the free flow of air through the window but which is so constructed and arranged that rain falling upon the shield will cause it to move into a position where it fully covers the window opening so that the rain cannot be driven through the window opening to the interior of the building.

The invention more specifically comprises a pivotally mounted shield normally disposed in outwardly and downwardly inclined position with respect to a window and having in association with a resilient means for maintaining the shield in opened position, a water receiver which upon becoming filled with rain-water, will overcome the holding action of the said resilient means and cause the shield to swing downwardly into a closed position with respect to the window opening. The water receiver is provided with means for slowly draining the water therefrom so that upon cessation of rainfall, the screen will automatically be re-opened so that fresh air may continue to pass through the adjacent window opening.

The invention will be best understood from a consideration of the following detailed description taken in connection with the accompanying drawing forming part of this specification, with the understanding, however, that the invention is not to be confined to any strict conformity with the showing of the drawing but may be changed or modified so long as such changes or modifications mark no material departure from the salient features of the invention as expressed in the appended claims.

In the drawing:

Fig. 1 is a view in elevation of a window showing the shield embodying the present invention, 55 in operative relation therewith.

Fig. 2 is a sectional view taken on the line 2—2 of Fig. 1.

Fig. 3 is a view in plan of the shield showing an extension piece connected therewith.

Referring now more particularly to the drawing, the numeral 1 generally designates a window frame in which are slidably mounted the usual upper and lower sash 2 and 3, respectively. Fitted within the window frame beneath the lower sash is a screen frame 4, the upper edge of which 10 would normally be engaged by the lower edge of the lower sash 3 while the lower bar of the screen frame rests upon the sill 5 in the usual manner.

In carrying out the present invention there is provided a plate 6 having a width substantially 15 the same as the inside width of the window between the vertically extending guide strips (not shown) which serve to maintain the window sashes in working relation and formed along one longitudinal edge of this plate is a rolled bead 7 20 which extends at its ends beyond the sides or side edges of the plate forming oppositely directed pivots or trunnions 9 which are designed to position between the sash guide strips as shown in Fig. 1.

The plate 6 is disposed in the window opening with the bead extending lengthwise of the lower edge of the sash 3 and interposed between the sash and the top bar of the screen frame 4, and the pivots or trunnions 9 positioned between the 30 guide strips for the sash, the bead engaging upon and being designed to turn on the top bar 4 of the window frame. Thus the plate 6 is adapted to swing in a vertical path and the height of the plate is such that when it has swung down to the 35 limit of its movement, the lower longitudinal edge will be disposed adjacent the front edge of the sill 5 so that the plate will effectively cover the opening beneath the raised sash 3.

The lower longitudinal edge of the plate 6 is 40 rolled, as shown is Fig. 2, to form a trough 10, the rolled back edge of the plate being spaced from the body to form the water inlet slot or opening 11. This trough 10 is provided with one or more drain apertures 12 which are sufficiently 45 small to prevent the rapid draining off of rain water as it falls upon the outer or top side of the plate when the latter is in raised position so that the trough will fill and the weight of the trapped water will cause it to swing downwardly 50 as hereinafter described.

Secured to the inner face of the plate 6 at approximately the central portion thereof is an upwardly opening hook bracket 13 and secured to the top of the window sill 5 is an upstanding 55

U-bracket 14 between the upright sides of which is oscillatably supported the short shaft 15 which forms a lateral extension of an arm 16. This arm has at its upper end a roller 17 which bears 5 against the inner side of the plate 6 and the roller is designed to be received in the hook bracket 13 so that the arm 16 will operate as a brace against the plate 6 to maintain it in raised position, in which position it will extend outwardly 10 and downwardly from the lower edge of the window sash 3, as shown in Fig. 2.

The shaft 15 has wound around it a coil spring 18, one end of which is suitably connected with the bracket 14 while the other end engages across 15 the inner side of the arm 16 so that the spring normally tends to urge the arm to swing outwardly in a direction which will maintain the roller 17 in the bracket 13. Thus it will be seen that if the lower or outer edge of the plate 6 is 20 forced down, the roller 17 will ride out of the bracket and upwardly across the inner side of the plate 6 toward the top thereof, swinging the arm 16 inwardly and placing the spring under additional tension. From this it will be readily 25 seen that the arm and spring unit will normally maintain the plate in opened position with respect to the adjacent window frame and that in the event of rainfall, the rain water will accumulate in the trough 10 and by properly proportioning 30 the size of the trough with respect to the strength of the spring, a sufficient weight of water will accumulate to overcome the tension of the spring and force the plate to swing downwardly to closed position. Thus the plate 6 will 35 operate as a shield to prevent the rain from being driven into the open window. After the rain stops falling, the water will gradually escape through the aperture 12 until the plate will be lightened sufficiently to permit the spring and 40 arm to again swing it outwardly to raised position.

In the form of the invention shown in Fig. 3, the plate 6a has the same form of bead at its upper end and trough at its lower end, as shown 45 in Figs. 1 and 2, these being indicated respectively by the numerals 1a and 10a but this structure shows a means of increasing the width of the plate to adapt it to a window of a width greater than the plate was initially designed to 50 fit. In this construction a suitable coupling is inserted in one end of the bead 1a as indicated at 19, and a similar coupling is inserted as indicated at 20, in one end of the trough 10a and there is then disposed in edge lapping relation 55 with the plate an auxiliary plate 21 having a bead and trough 22 and 23 which receive the coupling members 19 and 20. The outer end of the bead 22 is extended to provide the pivot trunnion 24 and the outer end of the trough 23 is closed 60 in the same manner as the opposite end of the trough 10a.

From the foregoing, it will be readily seen that with a device of this character mounted in a window frame at all times when it is desirable 65 that such window be kept open, there need be no fear of rain being driven into the window as the shield device will operate effectively to close the window opening shortly after the rain begins and after it has stopped, the device will automatically return to its opened position.

70 What is claimed is:

1. A shield for the opening of a window frame formed by an opened sash, comprising a shield plate having a width substantially equal to the

width of said opening, means at the ends of one longitudinal edge of the plate for pivotally supporting the same within said opening, said plate having a raised position with respect to the opening whereby air may pass therebeneath and through the opening and a lowered position with respect to the opening whereby the passage of air beneath the plate is shut off, an arm member oscillatably attached to the window frame beneath the plate and extending upwardly for contact with the underside of the plate, said arm being oscillatable outwardly to force the upper end thereof against the plate and to raise the plate to opened position, resilient means normally urging said arm to swing outwardly to move the plate to opened position, and water receiving means at the lower edge of the plate adapted to receive water falling upon the top of the plate and having a size sufficient to trap a quantity of water having a weight sufficient to force the 2 swinging of the plate downwardly to closed position against the action of said resiliently actuated arm.

2. A shield for the opening of a window frame formed by an opened sash, comprising a shield plate having a width substantially equal to the width of said opening, means at the ends of one longitudinal edge of the plate for pivotally supporting the same within said opening, said plate having a raised position with respect to the opening whereby air may pass therebeneath and through the opening and a lowered position with respect to the opening whereby the passage of air beneath the plate is shut off, an arm member oscillatably attached to the window frame beneath the plate and extending upwardly for contact with the underside of the plate, said arm being oscillatable outwardly to force the upper end thereof against the plate and to raise the plate to opened position, resilient means normally urging said arm to swing outwardly to move the plate to opened position, water receiving means at the lower edge of the plate adapted to receive water falling upon the top of the plate and having a size sufficient to trap a quantity of water having a weight sufficient to force the swinging of the plate downwardly to closed position against the action of said resiliently actuated arm, and means permitting the slow escape of water from said water receiving means whereby the resiliently urged arm may shift the plate to opened position when the water receiving means has been lightened to a sufficient degree.

3. A window rain shield designed to be mounted within a window opening, comprising a plate body having one longitudinal edge rolled to form a body on the axial center of which the plate may oscillate, said rolled edge having its ends extended beyond the transverse end edges of the plate to form trunnions for engagement between the sash guide strips of a window frame, the opposite longitudinal edge of the plate being rolled to form a water receiving trough, said trough having a drain opening, a supporting arm, means for oscillatably securing an end of the arm to the sill of a window frame beneath the plate, the other end of the arm being designed for sliding contact with the plate to act when in one position as a prop for the plate, and resilient means connected between the said securing means and the arm and normally acting to urge the arm into plate propping position.
